(57) **CLAIM**

I claim the ornamental design for a sanding block, as shown and described.

DESCRIPTION

FIG. 1 is a perspective view of a sanding block showing the new design;

FIG. 2 is a front elevational view of the sanding block, the rear elevational view being a mirror image of the front view; FIG. 3 is a left side elevational view of the sanding block, the right side elevational view being a mirror image of the left side view;

FIG. 4 is a top elevational view of the sanding block; and, FIG. 5 is a bottom elevational view of the sanding block.
